CLAIM

The ornamental design for an antenna, as shown and described.

DESCRIPTION

FIG. 1 is a front perspective view of an antenna of the present disclosure;

FIG. 2 is a rear perspective view of the antenna shown in FIG. 1;

FIG. 3 is a front elevational view of the antenna shown in FIG. 1;

FIG. 4 is a rear elevational view of the antenna shown in FIG. 1;

FIG. 5 is a left-side elevational view of the antenna shown in FIG. 1;

FIG. 6 is a right-side elevational view of the antenna shown in FIG. 1;

FIG. 7 is a top plan view of the antenna shown in FIG. 1; and,

FIG. 8 is a bottom plan view of the antenna shown in FIG. 1.

The broken lines shown in the drawings are for the purpose of illustrating portions of the antenna that form no part of the claimed design.

1 Claim, 8 Drawing Sheets
